[57] CLAIM

The ornamental design for a keyboard wrist rest, as shown and described.

DESCRIPTION

FIG. 1 is a front perspective view of the keyboard wrist rest showing our new design, on a reduced scale, the broken line drawing of a keyboard is for illustrative purposes only and forms no part of the claimed design;

FIG. 2 is a front side elevational view (upside down) of the keyboard wrist rest depicted in FIG. 1;

FIG. 3 is a top side view of the keyboard wrist rest of FIG. 1 showing two adhesive portions unconnected;

FIG. 4 is a right side elevational view of the keyboard wrist rest of FIG. 1, the left side elevational view is a mirror image of the right side elevational view;

FIG. 5 is a back side elevational view of the keyboard wrist rest depicted in FIG. 1; and

FIG. 6 is a bottom view of the keyboard wrist rest of FIG. 1 showing the pair of leg portions.
